[57] **CLAIM**

The ornamental design for a library unit for accepting
cantilevered document-storing components, as shown
and described.

DESCRIPTION

FIG. 1 is a front elevational view of a library unit for
accepting cantilevered document-storing components
showing our new design;

FIG. 2 is a right side elevational view, the left side being
substantially identical;

FIG. 3 is a rear elevational view;

FIG. 4 is a top plan view;

FIG. 5 is a bottom plan view; and

FIG. 6 is a front perspective view.
